United States Patent Office.

JOHN JOSEPH CHARLES SMITH, OF SOMERVILLE, ASSIGNOR TO THE METALLIC COMPRESSION CASTING COMPANY, OF BOSTON, MASSACHUSETTS, ASSIGNOR TO RUSSELL & ERWIN MANUFACTURING COMPANY, OF NEW BRITAIN, CONNECTICUT.

Design No. 4,130, dated June 7, 1870.

DESIGN FOR A BELL-PULL KNOB.

The Schedule referred to in these Letters Patent and making part of the same

---

I, JOHN JOSEPH CHARLES SMITH, of Somerville, county of Middlesex and State of Massachusetts, have invented and produced a new and original Design for a Bell-pull Knob, of which the following is a specification.

The nature of my design is represented in the accompanying photographic illustration, to which reference is made.

I claim the design for a bell-pull knob, substantially as above set forth.

JOHN JOSEPH CHARLES SMITH.
